[57] CLAIM

The mounting plate for automobile hi-fidelity system speakers, as shown and described.

DESCRIPTION

FIG. 1 is a rear elevation of mounting plate for automobile hi-fidelity system speakers showing my new design; FIG. 2 is a reduced front elevation thereof, with the grill screen omitted for ease of illustration; FIG. 3 is a top plan view thereof; FIG. 4 is a left side elevation thereof; FIG. 5 is a right side elevation thereof; FIG. 6 is a bottom plan view thereof; and FIG. 7 is a fragmentary cross-section taken on line 7—7 of FIG. 2.

The grill screen illustrated in FIGS. 3—6 inclusive is depicted slightly differently than said corresponding element disclosed in FIG. 1 due to the reduced size of the views.
